ENVELOPE SEALING MACHINE

Schuyler Arnold, Rochester, and Frederick Statt,
Coldwater, N. Y.; said Statt assignor to said
Arnold

Application March 7, 1935, Serial No. 9,814

20 Claims. (Cl. 120—6)

Our present invention relates to machines for gumming, folding and sealing envelopes and similar packages and it has for its object to provide a light simple and efficient machine of this character that will operate at a considerable speed and upon envelopes of various sizes and thicknesses. The improvements are directed in part toward adjustable features of the conveyor and guiding means to accommodate the different sized packages; toward the gumming and folding means and adjustable features thereof with relation to the conveyor, and toward means for maintaining the envelopes or packets in proper alignment on the conveyor so that their flaps will engage properly the gumming, folding and sealing means.

To these and other ends, the invention resides in certain improvements and combinations of parts, all as will be hereinafter more fully described, the novel features being pointed out in the claims at the end of this specification.

In the drawings:

Fig. 1 is a top plan view of an envelope machine constructed in accordance with and illustrating one embodiment of our invention;

Fig. 2 is a side elevation thereof;

Fig. 3 is an enlarged cross section through the gumming device and associated parts taken substantially on the line 3—3 of Fig. 2;

Fig. 4 is a fragmentary section taken on the line 4—4 of Fig. 3;

Fig. 5 is an enlarged section, partly broken away, taken on the line 5—5 of Fig. 1;

Fig. 6 is an enlarged cross section through the sealing irons taken substantially on the line 6—6 of Fig. 2;

Fig. 7 is an enlarged detail elevation of part of the folding elements, as they also appear in Fig. 2;

Fig. 8 is a detail cross section on the line 8—8 of Fig. 7;

Fig. 9 is an enlarged side elevation of a modified form of conveyor element;

Fig. 10 is a cross section, enlarged, taken substantially on the line 10—10 of Fig. 9;

Fig. 11 is a similar cross section through a further modified form of conveyor, and

Fig. 12 is a fragmentary side view, similar to Fig. 9, of the last mentioned modification.

Similar reference numerals throughout the several views indicate the same parts.

Referring first to the assembly views for a general idea of the arrangements and mode of operation of the machine, 1 indicates a bed along which the envelopes are propelled with their

flaps projecting laterally. These first engage a gumming device, indicated generally at 2, then a folding device, indicated generally at 3, that turns the gummed flap under the envelope and finally a sealing and drying device in the form of a pair of ironers, indicated generally at 4. The propelling element consists, in Figs. 1 to 5, of a pair of endless sprocket chains 5 and 6 provided with transversely aligned pairs of pins 7. It may be mentioned at this point that this particular embodiment of the invention has been designed for handling packets of seeds which are put up in the familiar end flap envelopes. The seeds are of widely different character as to both weight and size and as the quantity contained in different envelopes or packets is not uniform, the packets vary in thickness and bulk. The pins just described engage a longitudinal edge of the packets and, in connection with a guide wall 8, convey them positively along the bed so that they do not twist and destroy the alignment of the projecting flap with the various instrumentalities with which they are designed to successively cooperate. Other features of the machine addressed to the problem of coping with these irregularities in the article treated will later appear.

The conveyor chains 5 and 6 travel on sprockets 9 and 10, respectively. The sprockets 9 are fixed to shafts 11 and 12 having bearings in extensions at opposite ends of the general frame structure 13 of the machine. The sprockets 10 are splined to these shafts in grooves 14 to slide adjustably longitudinally thereof while locked to turn therewith. Shaft 12 is a driving shaft operated through belt 15 from a motor 16. Chain 35 5 travels in a fixed guide 17 in the frame, while chain 6 travels in a parallel guide 18 (Fig. 5) movable toward and from the same. With guide 18 is associated the guide wall 8 for the envelopes previously referred to and both are mounted on a carriage 19. Threaded into this carriage are two lead screws 20 and 21 having fixed bearings in the frame and whereby the aforesaid adjusting movements of the carriage are effected. Screw 20 is provided with a hand crank 22 and, through gearing 23 and 24 and a shaft 25, the two screws are turned in unison.

When this is done, the sprockets 10 will adjust themselves correspondingly to the position of the guide 18. The bed 1 is preferably in the form of a suitably faced wooden board, as shown, that may be lifted out during these adjustments and replaced by a board of greater or less width to exactly fill the space between the conveyor chain guides 17 and 18. Several boards are pro-

vided to correspond with the different standard sizes of envelopes.

A carriage 50 adjustable on the main frame 13 carries the gumming and folding units 2 and 3. It also carries a bracket 26 supporting a rest 27 for the envelope flap as it is gummed and folded. Adjacent to and fixed with respect to the guide 17 for the constant chain element 5 of the conveyor and between it and the rest 27 is a track 28 on which the envelope slides at its open end in the region of the base or connecting portion of the flap, it being understood that the envelope is laid on the conveyor with the flap continuous with its own top wall, so that the mouth is underneath and the flap is to be turned downwardly, inwardly and upwardly in sealing. Cooperating with this track 28 is an additional propelling and holding element for the envelopes in the form (in Figs. 1 to 8) of an endless rubber belt or strap 29. This is mounted on a sheave 30 carried by a bracket 31 at the initial end of the path of travel and by a sheave 32 on a bracket arm 33 at the other end, which arm is an extension of the bearing bracket for shaft 12. The arm forms a bearing for a stud shaft 34 to which is also fixed a gear 35 meshing with a gear 36 on driving shaft 12, by means of which the sheave and belt propeller 29 are driven.

The lower reach of the belt propeller is backed up and held in a definite path by a guide bar 37 mounted in a manner that will be hereinafter described. Thus, the envelope near its mouth is gripped between this moving yielding element and track 28 to perform two functions: In connection with the guide 8 for the opposite closed end of the envelope it holds the stuffed packets squarely against the companion pins 7 on the conveyor and it temporarily seals the envelope against escape of the contents.

Thus supported and conveyed, the envelope passes first to the gumming element 2 which consists essentially (Fig. 3) of a feeding and pasting drum 38 having a ribbed periphery 39 that travels substantially tangentially of the envelope carrying plane defined by the elements 6, 28, 27 and applies corresponding bands of glue transversely of the tip of the projecting envelope flap on the underside. The top side is correspondingly engaged by the ribbed periphery 40 of a presser roll on a stud shaft 41, the ribs thereof alternating with those on the feed drum, so that contact is assured. The drum 38 has a shaft 42 journaled in a glue box 43 and the stud 41 is carried by a bracket 44 vertically adjustable on the box through a supporting stem 45. A doctor blade 46 having adjusting devices 47 cooperates with the feed drum 38 in the usual manner.

Because the glue box has a relatively sliding support, as hereinafter described, the shaft 42 is preferably in open journals thereon and is suitably coupled at its inner end to a jack shaft 48 carried by the main frame and which, through a sprocket and chain connection 49, is driven from shaft 11. The said support consists of a carriage 50 having ways 51 in which the glue box slides toward and from the envelope conveying path in connection with an angle bracket 52 fixed on the carriage and slotted at 53 to take a threaded post 54 fixed to the box and provided with a winged clamping nut 55. The carriage is provided with a suitable contained electric heating device 56 beneath the ways 51 to keep the glue warm and prevent it from congealing.

The foregoing mobility of the glue box provides for a fine adjustment of the gumming unit

alone. It is also bodily movable with the carriage 50 through the medium of lead screw 57 threaded in the frame 13 and having a thrust bearing 58 in the carriage with an operating crank 59 at the opposite side of the machine. As the flap folding unit 3 must be correspondingly adjusted to adapt it to the same differences in size and shape of the envelope flap, this unit is mounted on a lateral extension of the carriage projecting from the ways adjacent to the screw 57, indicated at 60 (see Figs. 2 and 3) and consists of a plow-point element 61 (Figs. 5 and 7) for initially turning the flap downwardly and a relatively reversed plow-point element 62 (see also Fig. 8) for turning it upwardly again. The former is vertically adjustable by means of set screws 63 and 64 upon a post 65 on the carriage 50 and has a portion including an extension 66 overhanging the flap rest 27 to prevent the flap from rising therefrom, the said extension 66 extending to the region of the element 62 to perform the same function there. The element 62 is similarly mounted on a post 67 on the carriage 50 to be adjusted up and down by means of a set screw 68 beneath the extension 66. In this way, both folding elements may be positioned properly with respect to the rest 27 with which they constitute, in effect, a slot through which the flaps are conducted and all are adjustable bodily with the carriage toward and from the track 28.

After passing through the folding device, the closed flap and outer end of the envelope runs through a sealing and drying device to cause the adhesive to take immediate hold. This consists in the present instance, of a lower iron 69 and an upper iron 70. The lower one is mounted upon a bracket 71 on the main frame and is provided with a suitable electrical heating unit 72. The upper one is adjustable toward and from its mate 40 by means of a pair of thumb screws 73 through which the iron is supported from overhanging bracket extensions 74. These same extensions carry other thumb screws 75, by means of which the guide or backing 37 for the belt 29 is supported and rendered adjustable to make a more or less intimate contact of the belt with the track 28, before described.

With the packets thus held during transit by the pins 7, guide wall 8 and pressing and impelling belt 29, it is still sometimes desirable, in view of the different thicknesses and weights of seed packages particularly, to provide a retarding device that will engage them bodily and exert a slight frictional resistance that will tend to hold them square against the pins. In the present instance, we provide such an instrumentality in the form of a suitably faced board 76. This is pivotally connected at 77 to the lower end of a link 78, the upper end of which rocks on an arm 79 slidably adjustable as to height through a thumb screw 80 on a post 81 rising from the chain guide carrying element 19. This board rides on the packets more or less lightly according to the elevation of the arm 79 and performs the function stated.

In Figs. 9 to 12, I have illustrated modified constructions of the closing or clamping and propelling couple represented by the track 28 and belt 29. In both of these forms, instead of the fixed track 28 of the first embodiment, the track is movable also, being constituted by the upper reach of a chain conveyor 28^a running over sprockets 28^b and 28^c in unison with an upper propelling chain 71^a so that the packet is gripped 75.

on both sides instead of being gripped on one side and sliding on the other. The upper chain passes over sprockets 32^a and alternate links carry soft rubber blocks 29^a suitably secured thereto in the embodiment of Figs. 9 and 10 instead of the continuous surface of belt 29. The lower track chain 28^a is provided with similar gripping blocks, as indicated, which cooperate respectively with units on the upper chain. This constitutes a positive feed in itself, through the use of which the main conveyor 5-6 may be made less elaborate or eliminated altogether.

In the further modification of Figs. 11 and 12, chains 37^a and 28^a are faced with continuous strips of rubber 29^b instead of the spaced or intermittent blocks similar to the rubber belt 29 of the first form. In this case, such strips, which are fastened to the chain suitably as by the bolts 82, take the place of the belt 29, while in both the modifications the chain 37^a functions as does the guide 37, in that the weight of the chain may be such as to hold the rubber contacts down against the packets with sufficient pressure to obtain the necessary grip.

25. We claim as our invention:

1. In a sealing machine of the character described, the combination with a frame, of a pair of parallel conveyors for jointly carrying envelopes along a given path, gumming and folding devices 30 for the envelope flaps arranged adjacent to a constant unit of the pair, and means for adjusting the other unit toward and from the constant unit.

2. In a sealing machine of the character described, the combination with a frame, of a pair 35 of parallel conveyors for jointly carrying envelopes along a given path, gumming and folding devices for the envelope flaps arranged adjacent to a constant unit of the pair, a guide wall for the envelopes fixed with respect to the other unit, 40 and means for adjusting the latter and the guide wall toward and from the constant unit.

3. In a sealing machine of the character described, the combination with a frame, of a pair 45 of parallel conveyors for jointly carrying envelopes along a given path, gumming and folding devices for the envelope flaps arranged adjacent to a constant unit of the pair, means for adjusting the other unit toward and from the constant unit, and a plurality of interchangeable bed plates of different widths fitting between the conveyors.

4. In a sealing machine of the character described, the combination with a frame, of a pair 55 of parallel conveyors for jointly carrying envelopes along a given path, gumming and folding devices for the envelope flaps arranged adjacent to a constant unit of the pair, means for adjusting the other unit toward and from the constant unit on one side thereof, a carrier for the gumming device, and means for adjusting the carrier to move the latter transversely toward and from the constant unit on the other side thereof.

5. In a sealing machine of the character described, the combination with a frame, of a pair 65 of parallel conveyors for jointly carrying envelopes along a given path, gumming and folding devices for the envelope flaps arranged adjacent to a constant unit of the pair, means for adjusting the other unit toward and from the constant unit on one side thereof, a carrier for the folding device, and means for adjusting the carrier to move the latter transversely toward and from the constant unit on the other side thereof.

6. In a sealing machine of the character described, the combination with a frame, of a pair 70 of parallel conveyors for jointly carrying en-

velopes along a given path, gumming and folding devices for the envelope flaps arranged adjacent to a constant unit of the pair, means for adjusting the other unit toward and from the constant unit on one side thereof, a common carrier for the gumming and folding devices, and means for adjusting the carrier to move the latter transversely toward and from the constant unit on the other side thereof.

7. In a sealing machine of the character described, 10 the combination with a frame, of a pair of parallel endless conveyor chains for jointly carrying envelopes along a given path, means on said chains for engaging and advancing the envelopes therewith, a pair of shafts provided 15 with sprockets for the chains including a driving shaft, one pair of sprockets being longitudinally adjustable on the shafts toward and from the other, and a chain guide for the chain on the adjustable sprockets movable toward and 20 from the other chain.

8. In a sealing machine of the character described, the combination with a frame, of a pair of parallel endless conveyor chains for jointly carrying envelopes along a given path, means on 25 said chains for engaging and advancing the envelopes therewith, a pair of shafts provided with sprockets for the chains including a driving shaft, one pair of sprockets being longitudinally adjustable on the shafts toward and from the other, 30 a chain guide for the chain on the adjustable sprockets having a guide wall for envelopes associated therewith, and means for adjusting the chain guide and guide wall toward and from the other chain.

9. In a sealing machine of the character described, the combination with a frame, of a pair of parallel conveyors for jointly carrying envelopes along a given path, gumming and folding devices for the envelope flaps arranged adjacent 40 to one of the conveyors and a yielding frictional retarding device arranged between the conveyors to trail upon envelopes carried thereby.

10. In a sealing machine of the character described, the combination with a frame, means for 45 conveying envelopes successively along a given path thereon, a guide for the closed end of the envelope associated with said means at one side, gumming and folding devices adjacent to the other side into cooperation with which the flap 50 of the envelope is adapted to project, of a track arranged between the gumming and folding devices and the conveyor means on which the portion of the envelope at the base of the flap is adapted to travel, and a yielding traveling frictional element superposed upon the track to engage the top of the last mentioned portion of the envelope and hold it against twisting.

11. A sealing machine constructed in accordance with claim 10 further characterized by the 60 fact that sheaves are provided at the ends of the path of travel and the traveling frictional element consists of a rubber belt passing on said sheaves.

12. A sealing machine constructed in accordance 65 with claim 10 further characterized by the fact that the track is in the form of an endless traveling member.

13. A sealing machine constructed in accordance with claim 10 further characterized by the 70 fact that the track is composed of an endless traveling member and the cooperating surfaces of it and the frictional element are composed of spaced rubber blocks mounted thereon.

14. A sealing machine constructed in accordance 75

ance with claim 10 further characterized by the fact that the traveling frictional element consists of a rubber belt and there is provided in combination a fixed groove track above the first mentioned track that backs up and guides the belt.

15. In a sealing machine of the character described, the combination with a frame and means for conveying envelopes successively along a given path thereon, of gumming and folding devices at one side of said path into which the envelope flap is adapted to project, the folding device embodying a bracket having a fixed rest for the underside of the flap, a pair of posts on the bracket, a plow-point folder overhanging and adjustable relatively to the rest on one post to turn the flap downwardly, and a plow point folder adjustable on the other post and beneath the overhang of the first folder to turn the flap upwardly.

16. In a sealing machine, the combination with a bed along which envelopes may travel and a narrow track at one side thereof, of gumming and sealing devices adjacent to the track into which the flaps of the envelopes may project, and a yielding traveling frictional propelling device cooperating with the track to temporarily seal the mouth of the envelope during the gumming and folding operations.

17. In a sealing machine, the combination with a bed along which envelopes may travel and a narrow track at one side thereof, of gumming and sealing devices adjacent to the track into which the flaps of the envelopes may project, and a yielding traveling frictional propelling device cooperating with the track to temporarily seal the mouth of the envelope during the gumming and folding operations, said propelling device consisting of an endless belt having a rubber facing.

18. In a sealing machine, the combination with a bed along which envelopes may travel and a

narrow track at one side thereof, of gumming and sealing devices adjacent to the track into which the flaps of the envelopes may project, a yielding traveling frictional propelling device cooperating with the track to temporarily seal the mouth of the envelope during the gumming and folding operations, and a rest for the underside of the flap between the gumming and sealing devices and the track.

19. In a sealing machine, the combination with a bed along which envelopes may travel and a narrow track at one side thereof, of gumming and sealing devices adjacent to the track into which the flaps of the envelopes may project, a yielding traveling frictional propelling device co-¹⁵ operating with the track to temporarily seal the mouth of the envelope during the gumming and folding operations, a rest for the underside of the flap between the gumming and sealing devices and the track, and a carriage movable toward and from the track upon which the gumming and sealing devices and the rest are collectively mounted.

20. In a sealing machine, the combination with a bed along which envelopes may travel, a guide wall for the bases of the envelopes at one side of the bed and adjustable toward and from the latter, and a narrow track at the other side of the bed, of gumming and sealing devices adjacent to the track into which the flaps of the envelopes may project, a yielding traveling frictional propelling device cooperating with the track to temporarily seal the mouth of the envelope during the gumming and folding operations, a rest for the under-³⁰ side of the flap between the gumming and sealing devices and the track, and a carriage movable toward and from the track upon which the gumming and sealing devices and the rest are collectively mounted.

SCHUYLER ARNOLD. 40
FREDERICK STATT.
